(57) **CLAIM**

The ornamental design for a pants binder, as shown and described.

DESCRIPTION

FIG. 1 is a top perspective view of the pants binder;
FIG. 2 is a bottom perspective view of the pants binder;
FIG. 3 is a top perspective view of the pants binder and shows ends of the pants binder snapped together;
FIG. 4 is a top plan view of the pants binder;
FIG. 5 is a bottom plan view of the pants binder;
FIG. 6 is a front elevational view of the pants binder shown in FIG. 1, the rear elevational view being a mirror image thereof;
FIG. 7 is a front elevational view of the pants binder shown in FIG. 2, the rear elevational view being a mirror image thereof;
FIG. 8 is a right elevational view of the pants binder shown in FIG. 7, the left elevational view being a mirror image thereof;
and,
FIG. 9 is a right elevational view of the pants binder shown in FIG. 6, the left elevational view being a mirror image thereof.
The broken line showing is for environmental purposes only and forms no part of the claimed design.
